ALTAR

Sylvia H. Bank, Los Angeles, Calif.

Application April 3, 1950, Serial No. 8,950

Term of patent 14 years

(Cl. D29—23)

To all whom it may concern:

Be it known that I, Sylvia H. Bank, a citizen of the United States of America, residing at Los Angeles, in the county of Los Angeles and State of California, have invented a new, original, and ornamental Design for Altar, of which the following is a specification, reference being had to the accompanying drawing, forming part thereof.

I claim:

The ornamental design for an altar, as shown.
SYLVIA H. BANK.
